DESIGN FOR A COMBINED SPOON AND
RATTLE

Richard B. Grosvenor, Piqua, Ohio

Application March 23, 1946, Serial No. 127,866

Term of patent 3½ years

(Cl. D34—15)

To all whom it may concern:

Be it known that I, Richard B. Grosvenor, a citizen of the United States, residing at Piqua, in the county of Miami and State of Ohio, have invented a new, original, and ornamental Design for a Combined Spoon and Rattle, of which the following is a specification, reference being had to the accompanying drawing, forming part thereof.

Figure 1 is a front elevational view of a combined spoon and rattle, showing my new design, Figure 2 is a side elevational view, and Figure 3 is a top plan view thereof.

I claim:

The ornamental design for a combined spoon and rattle, as shown.

RICHARD B. GROSVENOR.
